UNITED STATES PATENT OFFICE.

RUTH M. HANSEN, OF DULUTH, MINNESOTA.

MANUSCRIPT CASE.

Application filed August 24, 1925. Serial No. 51,942.

To all whom it may concern:

Be it known that I, RUTH M. HANSEN, a citizen of the United States, residing at Duluth, in the county of St. Louis and State 5 of Minnesota, have invented certain new and useful Improvements in Manuscript Cases, of which the following is a specification, reference being had therein to the accompanying drawing.

10 This invention relates to manuscript cases or holders for loose leaf tablets and has special reference to one particularly adapted for holding a loose leaf tablet when being written upon, and also during transportation by mail; the principal object being to provide such a holder having exceptionally convenient features of adjustment and adaptability.

Another object is that of providing such a 20 manuscript case exceptionally adaptable for filing and ready reference by the recipient.

Other objects and advantages will appear in the further description of the invention.

Referring now to the accompanying drawing, forming part of this application, and in which like reference characters indicate like parts:

Figure 1 is a perspective view of one of the improved holders,

30 Figure 2 is a central vertical section of Fig. 1, and

Figure 3 is a plan view of the reference card associated with the case.

1 represents a comparatively rigid back 35 or body portion which may be of wood, heavy cardboard, or the like, and preferably somewhat larger in size than the sheets of blank paper which are used, as indicated at 2. The back is provided adjacent one end 40 with a plurality of spaced holes indicated at 3 and 4, while in the central portion of the opposite end there are two holes 5 and 6 spaced longitudinally of the back and from the extreme end thereof. A securing flap 7, 45 preferably of leather or the like, is fastened within the two holes 5 and 6 by means of the common paper fasteners 8 and 9, while at 10 is shown a snap button carried upon the face of the cover member 11 so 50 that the free end of the flap or keeper 7 may be snaped onto said button when the case is closed. It will be noted that there are two or three additional holes 12 in the keeper aligned with the holes through which the 55 paper fasteners 8 and 9 are shown so that in the event of the stack or pad of paper 2

varying in thickness the length of the keeper 7 may also be varied by placing the fasteners 8 and 9 in different ones of these holes as is obvious.

60 This same form of adjustment is provided for the engagement of the end of the cover member 11 with the opposite end of the body member 1, there being shown the fasteners 13 which hold the extreme end of the cover member 11 tightly against the body portion 1, while the fasteners 14 extend through the loose leaves of the pad and through the body portion 1 and cover 11 where their free ends are clinched as clearly illustrated. Intermediate holes as indicated at 15 are provided 65 for optional placing of the fasteners.

70 For convenience of reference by the recipient of such a manuscript case I have provided a flap pocket indicated at 16 on 75 the face of the cover into which a card may be placed bearing the title, author's name, address, etc., as desired, so that the case is a complete and readily identified unit. This pocket is preferably provided with a transparent face, such as celluloid or the like, behind which the card, indicated at 17, may be placed, the indicia on said card appearing 80 through the window of the pocket.

85 On the card 17 is printed in a vertical column, as indicated in the center thereof, a list of the forms of articles in which the recipient is supposed to be interested, for example those of certain editors or publishers, and after each form thus indicated 90 is a square to be checked, so that there may be seen at a glance to what the contents of the case refers. There is also printed upon this card the particular title of the manuscript and the author's name and address, so 95 that when received by a publisher for consideration the manuscript will be found in the most readily identified manner possible, the object of which is obvious.

100 Having thus described my invention, what I claim and desire to secure by Letters Patent, is:

1. The combination with a manuscript case of the character described composed of a rigid body member and a flexible cover 105 member overlapping one end of the body member there being a plurality of holes in the overlapped ends of the members registrable with each other, manuscript leaves having holes therein registrable with holes 110 in the cover and body members, a row of removable fastening means in registering holes

for uniting the members together with the manuscript leaves, and a second series of removable fasteners in other registering holes to hold in place against the rigid member 5 the overlapping end of the flexible member.

2. A manuscript case comprising a rigid back having a plurality of holes adjacent its binding edge, manuscript leaves having holes therein registerable with holes in the 10 back, a flexible cover member for covering

the manuscript and overlapping the binding edges of the back and manuscript and having holes in its overlapping end registerable with holes in the back, and removable fastening means within registering holes of the 15 leaves, back and cover for holding the same together.

In testimony whereof I hereunto affix my signature.

RUTH M. HANSEN.
